PLAYING CARD RACK

Clyde H. Clement, 1423 S. 28th St., Phoenix, Ariz.

Filed Feb. 12, 1960, Ser. No. 59,372

Term of patent 14 years

(Cl. D34—13)

FIG. 2

FIG. 1

FIG. 3

FIG. 4

FIG. 7

FIG. 5

Figure 1 is a front elevational view of the rack;
of the end faces broken away to show the central portions of the rack in section.

I claim:

The ornamental design for a playing card rack, as shown.
